[57] CLAIM

The ornamental design for a battering ram, as shown and described.

DESCRIPTION

FIG. 1 is a top front and one side perspective view of a battering ram showing a first embodiment of my new design;

FIG. 2 is a bottom plan view thereof;

FIG. 3 is an opposite side elevational view thereof;

FIG. 4 is a rear elevational view thereof;

FIG. 5 is a top, front and one side perspective view of a battering ram showing a second embodiment of my new design;

FIG. 6 is a bottom plan view thereof;

FIG. 7 is a rear elevational view thereof.

FIG. 1

FIG. 2

FIG. 3

FIG. 4

FIG. 5

FIG. 6

FIG. 7
